AUTOMATIC COMPRESSOR UNLOADER

Charles G. Bach, Milwaukee, Wis., assignor to The
Vilter Manufacturing Company, Milwaukee,
Wis., a corporation of Wisconsin

Application May 21, 1938, Serial No. 209,201

12 Claims.

(Cl. 230—21)

My present invention relates generally to improvements in the art of compressing fluids, and relates more specifically to improvements in the construction and operation of automatic unloading devices for gas compressors or the like.

Generally defined, an object of my present invention is to provide an improved automatic unloader for compressors, which is simple in construction and efficient in operation.

10 A more specific object of the invention is to provide an improved compressor unloader of the clearance pocket type and especially applicable to refrigerant gas compressors, which is extremely simple and compact in construction, and which is 15 moreover rapid and reliable in operation.

While numerous types of so-called clearance pocket unloaders for refrigerant compressors, have heretofore been proposed, none of these prior devices have proven entirely satisfactory in 20 commercial use, primarily because of their complicated structure and their failure to operate properly under varying conditions of operation of the compressors. These unloading mechanisms which are used in conjunction with various types

25 of air and gas compressors, ordinarily include one or more clearance pockets which are communicable past automatically operable control valves, with the displacement chamber of the pump or compressor, so as to vary the capacity

30 of the pressure pump in accordance with the demand for compressed fluid. The unloading valve or valves are ordinarily controlled either by means of thermostat located in the compressor suction line, or by an automatic pressure switch, or they 35 may be controlled in any other suitable manner. It is necessary that the unloading valves be operable quickly and positively, if effective unloading is to be accomplished, and undue complications in these assemblages will necessarily detrimentally affect the accuracy and reliability of 40 performance.

In accordance with my present improvement, I locate the clearance pocket of the unloading assemblage in the wall of the compressor cylinder 45 and connect the same through a large valve controlled port directly with the delivery end of the displacement chamber, and through a small constantly open passage directly with the suction line. The control valve for the large port is 50 operable to close the same by pump discharge pressure acting upon a valve actuating plunger, and to open the same by means of a simple spring coacting with the same plunger in opposition to the valve closing pressure. Release of the high 55 valve actuating pressure is effected by means of

a simple magnetically actuated by-pass valve controlled by a thermostat or by a pressure switch, and the entire system is so simple and foolproof in operation, that maximum efficiency must necessarily result. The operation of my improved unloading mechanism is also entirely automatic after proper initial adjustments have been made, and the device can be manufactured and installed at moderate cost and requires little attention.

A clear conception of an embodiment of the present invention, and of the mode of constructing and of operating automatic compressor unloaders built in accordance with the improvement, may be had by referring to the drawing accompanying and forming a part of this specification wherein like reference characters designate the same or similar parts in the various views.

Fig. 1 is a fragmentary sectional view showing 20 a portion of a compressor cylinder, piston and discharge valve mechanism, and also disclosing the internal structure of one of my improved clearance pocket unloaders and the connections associated therewith;

Fig. 2 is a transverse vertical section through 25 the unloader, taken along the line 2—2 of Fig. 1 and drawn to a reduced scale; and

Fig. 3 is a section through the magnetically operated valve which is used in the unloader control system.

While I have shown an automatic compressor unloader which is especially applicable to a particular type of high pressure reciprocating single-acting compressor for handling refrigerant gases such as ammonia and "freon", it is not the intent 35 to thereby unnecessarily restrict the scope.

Referring to the drawing, the high pressure compressor shown therein is of relatively standard construction and comprises a cylinder 6 having a bore 7; a piston 8 reciprocable within the bore 7 40 and having one or more suction valves 9 associated directly therewith; and an end head 10 sealing the bore 7 and cooperating with the piston 8 to form a displacement chamber 11, the head 10 being provided with one or more discharge valves 45 12 normally held to their seating by means of annular helical springs 13.

My improved automatic unloader which is associated directly with the gas compressor, comprises generally a clearance pocket 14 of any desired volume formed in the cylinder 6 and communicating through a small passage 15 with the compressor suction space; a relatively large port 16 connecting the pocket 14 with the displacement chamber 11 at the extreme end of the 55

compression stroke of the piston 8; a main unloading valve 17 for controlling the delivery of compressed gas to and from the chamber 11 and the pocket 14 through the port 16, and having a stem 18 to the outer end of which a valve 5 actuating plunger 19 is rigidly attached; a casing 20 secured to the cylinder 6 and having therein a bore 21 with which the plunger 19 coacts and which is divided by this plunger into chambers 22, 23; a compression spring 24 disposed within the chamber 22 and coacting at its opposite ends with the casing 20 and with the plunger 19; a closure plate 25 for the chamber 23 and providing a support for an adjustable 10 screw 26 for locking the valve 17 in closed position; a magnetically operated pressure relief valve 27 automatically operable by a device 28 and being communicable through a pipe 29 with the chamber 23, and through another pipe 30 with the chamber 22 and with a suction connection 31; and a high pressure inlet connection 32 communicating with the chamber 23. While the movement of the plunger 19 along the bore 21 is such that the piston may materially 15 reduce the area of the port or connection 32 which admits high pressure gas to the chamber 23, this port should never be completely cut off, and the spring confining chamber 22 may also be provided with a small port 33 (shown in 20 dot-and-dash lines in Fig. 1) which communicates with the suction line and which may be sealed by the plunger 19 when the unloading valve 17 is closed.

The clearance pocket 14 may be formed directly in the cylinder 6 or in a separate casting, and there may be any desired number of these pockets and corresponding unloading mechanisms. The suction passage 15 should be relatively small, and may be omitted and replaced by venting clearance between the stem 18 and casing 20, and these vent passages are provided primarily for the purpose of preventing excessive pressure from building up in the pocket 14, and which would tend to keep the valve 45 17 closed. The valve 17 coacts with a bevel seat 34 and may be flexibly and detachably connected to the inner end of the stem 18 by means of a threaded collar 35 and a spring 36 coacting with an enlarged end of the stem, so as to insure tight seating.

The casing 20 which houses the plunger 19, may be removably attached to the cylinder 6 by means of studs 37, and the closure plate 25 55 may be likewise attached to the casing 20 by studs 38. A ring nut 39 serves to firmly attach the plunger 19 to the stem 18, and the plunger 19 is preferably of somewhat less diameter than the bore 21 and is provided with sealing rings 60 40 for throttling the port 32 and for preventing leakage of gas from the chamber 23 to the chamber 22. The adjustable screw 26 has screw thread coaction with the closure plate 25, at its inner end, and has its outer end provided with a polygonal actuating portion which is normally confined and sealed within a detachable cap 41. The locking screw 26 should also preferably be 65 braced by packing material 42 in order to prevent escape of high pressure gas therealong from the chamber 23 which, as previously stated, is in constant communication with the high pressure discharge line of the compressor through the port or connection 32. The suction connection 31 may be omitted, but if provided, should 70 be of restricted cross-section or should be var-

iable in cross-section with the aid of a needle valve.

The automatic controlling device 28 may be either a thermostat operable by suction temperature, or a pressure switch, or any other type of apparatus for completing an electric circuit for actuating the magnetic valve 27. This valve 27 may be of extremely simple and compact construction as shown in detail in Fig. 3, and comprises a casing having ports communicating with the pipes 29, 30 respectively, and also having a valve seat 43 therein; a valve plunger 44 normally held against the seat 43 by gravity and having an upper bar portion 45; and a coil 46 embracing the bar portion 45 and adapted to lift the valve plunger 44 against a stop 47 when the coil 46 is energized. The valve 27 may be located any desired distance from the device 28, and may even be built into the casing 20, and when the plunger 44 is seated as in Fig. 3, high pressure gas is confined within the chamber 23, and the chamber 22 is open to suction through the pipes 30, 31, thereby causing the unloading valve 17 to remain closed as shown in the drawing.

During normal operation of the compressor, and when maximum discharge capacity is required, the unloading mechanism will not be functioning, as the valve 17 will remain closed and the pocket 14 will be vented to suction through the passage 15, or past the stem 18 to the chamber 22. The high-pressure discharge pressure will be established and maintained in the chamber 23 through the connection 32, and the spring 24 will then be compressed within the chamber 22 which is also vented to suction through the pipes 30, 31.

When the device 28 is actuated to energize the magnetic coil 46, as by reduction in load on the low pressure side of the compressor, the valve plunger 44 will be raised thus permitting high pressure gas to escape from the chamber 23 past the valve 27 to the chamber 22 and to the suction line. This reduction or release of pressure in the chamber 23 causes the spring 24 aided by the high discharge pressure in the chamber 11, to become quickly effective to open the unloading valve 17 and to throttle the admission of fresh high pressure gas through the connection 32, and the opening of the valve 17 permits some of the high pressure gas displaced by the reciprocating piston 8 to surge into and out of the pocket 14 as the piston approaches and recedes from the port 16. While a negligible quantity of the gas admitted to the pocket 14 during the compression stroke of the piston 8, escapes to the suction line through the restricted passage 15 or past the valve stem 18 most of this gas is returned to the displacement chamber 11 during the suction or return stroke of the piston; and if any high pressure gas is trapped within the pocket 14 due to sudden closing of the valve 17, this gas will escape to the suction line through the passage 15, or past the stem 18 to the chamber 22. If the port 33 is used, this port will be uncovered when the plunger 19 is moved toward the screw 26 during opening of the valve 17, and will assist the suction pipe 31 in releasing pressure from within the chamber 22; but it may be desirable to have the port 33 normally closed and the connection 31 so restricted, that gas under pressure released from the chamber 23 may act momentarily through the pipes 29, 30 to build up a slight gas

pressure in the chamber 22 which will assist the spring 24 in opening the valve 17.

When the device 28 operates to break the electric circuit and to thereby deenergize the coil 46, the valve plunger 44 drops and thus closes the valve 27 thus cutting off the escape of gas from the chamber 23 through the pipe 29. High pressure gas then quickly fills the chamber 23 and acts upon the plunger 19 in opposition to the spring 24 to close the unloading valve 17. In this manner, the unloading valve 17 will be quickly and positively opened and closed in response to the action of the controlling device 28, and when the valve 17 is closed, the pressure in the pocket 14 will be quickly relieved, and the port 33 and pipe 31 will likewise quickly relieve the gas pressure from the chamber 22. The adjustable screw 26 may be readily adjusted to prevent opening movement of the valve 17, and to also prevent complete closing of the port connection 32, by merely removing the cap 41 and by applying a wrench to the polygonal outer end of the stop 28; and the plate 25 and casing 26 may be conveniently removed to permit inspection of internal parts, by releasing 25 the nuts coating with the studs 38, 37.

From the foregoing detailed description it will be apparent that my present invention provides an extremely simple and compact automatically functioning unloading assemblage which is positive and reliable in action, and which may moreover be conveniently applied to standard air or other gas compressors. The extent of unloading will be dependent upon the periods for which the valve 17 is retained open, and the length of these periods will be dependent upon the action of the control device 28. All portions of the improved assemblage, besides being extremely simple in structure, are conveniently accessible for inspection and adjustment, and the unloader has proven 40 highly successful and satisfactory in actual use. The venting of the clearance pocket 14 by means of a passage 15 or otherwise, is relatively important, since this venting prevents accumulation of undesirably high gas pressure in the clearance pocket; and the throttling of the port connection 32 by the valve actuating plunger 19 in order to prevent the high pressure gas from rushing into the chamber 23 when the valve 27 opens, is also desirable. If this inrush of high pressure gases is 45 not checked, the pressure in the chamber 23 will build up faster than it can be relieved by opening of the relatively small valve 27, and the spring 24 will be restrained from moving the plunger 19 to valve opening position. The magnetic valve 27 is 50 also of extremely simple and compact construction, and all elements of the assemblage may obviously be manufactured, assembled and applied to a compressor system at moderate cost.

It should be understood that it is not desired to 55 limit this invention to the exact details of construction, or to the precise mode of use herein shown and described, for various modifications within the scope of the claims may occur to persons skilled in the art.

60 I claim:

1. In combination with a compressor having suction and discharge valves and a piston displacement chamber communicable therewith, a clearance pocket communicable with the piston displacement chamber and having constant restricted communication with the suction line, an unloading valve for controlling communication between said pocket and said chamber, and a plunger for operating said valve, said plunger being movable to close said valve by compressor dis-

charge pressure and to open said valve by mechanical means.

2. In combination with a compressor having suction and discharge valves and a piston displacement chamber communicable therewith, a clearance pocket communicable with the piston displacement chamber at the end of the compression stroke of the piston and having a constantly open vent communicating with the compressor suction, an unloading valve for controlling communication between said pocket and said chamber, a plunger operable outside of said pocket for actuating said valve, means for subjecting said plunger to high fluid pressure to close said valve, and spring means for opening said valve when said high fluid pressure is released.

3. In combination with a compressor having suction and discharge valves and a piston displacement chamber communicable therewith, a clearance pocket communicable with the piston displacement chamber at the end of the piston compression stroke, an unloading valve for controlling communication between said pocket and said chamber, means forming an auxiliary chamber out of communication with said pocket and disposed in alignment with said valve, a valve actuating plunger movable in said auxiliary chamber, means for subjecting one side of said plunger to compressor discharge pressure and the opposite side thereof to suction, and spring means for moving said plunger when the discharge pressure acting thereon is released.

4. A compressor unloader comprising, a clearance pocket communicable with the compressor displacement chamber and being constantly vented to the compressor suction, an unloading valve for controlling communication between said clearance pocket and the compressor displacement chamber, a plunger movable in one direction by compressor discharge pressure to close said valve and in the opposite direction by spring pressure and means operable by variations in compressor suction pressure for by-passing high pressure fluid from one side of said plunger to the other.

5. A compressor unloader comprising, a clearance pocket communicable with the compressor displacement chamber at the end of the piston compression stroke, an unloading valve for controlling communication between said pocket and said displacement chamber, and a plunger subjected to compressor discharge pressure to close said valve and to spring pressure to open said valve, said plunger being movable to throttle the admission of said discharge pressure when said valve is opened.

6. A compressor unloader comprising, a clearance pocket communicable with the compressor displacement chamber, an unloading valve for controlling communication between said pocket and said displacement chamber, a valve actuating plunger disposed outside of said pocket, a spring cooperable with said plunger to open said valve, and means for subjecting said plunger to compressor discharge pressure to close said valve.

7. A compressor unloader comprising, a clearance pocket communicable with the compressor displacement chamber, an unloading valve for controlling communication between said pocket and said displacement chamber, a valve actuating plunger disposed outside of said pocket, a spring cooperable with said plunger to open said valve, means for subjecting said plunger to compressor discharge pressure to close said valve, and means

for releasing pressure from said pocket to the compressor suction when said valve is closed.

8. A compressor unloader comprising, a clearance pocket communicable with the compressor displacement chamber, an unloading valve for controlling communication between said pocket and said displacement chamber, a valve actuating plunger disposed outside of said pocket, a spring cooperable with said plunger to open said valve, means for subjecting said plunger to compressor discharge pressure to close said valve, and a constantly open restricted vent for said pocket communicating with the compressor suction.

9. A compressor unloader comprising, a clearance pocket communicable with the compressor displacement chamber, an unloading valve for controlling communication between said pocket and said displacement chamber, a valve actuating plunger disposed outside of said pocket, a spring cooperable with said plunger to open said valve, and means for subjecting said plunger to compressor discharge pressure to close said valve, and a constantly open restricted vent for said pocket communicating with the compressor suction.

10. A compressor unloader comprising, a clearance pocket communicable with the compressor displacement chamber at the end of the compression stroke, an unloading valve for controlling communication between said pocket and said displacement chamber, a valve actuating plunger disposed outside of said pocket, a spring cooperable with said plunger to open said valve, and means for subjecting said plunger to compressor discharge pressure to close said valve, said plunger being movable to throttle the admission of compressor discharge pressure thereto when said valve is open.

11. A compressor unloader comprising, a clearance pocket communicable with the compressor displacement chamber at the end of the compression stroke, an unloading valve for controlling communication between said pocket and said displacement chamber, a plunger operable by compressor discharge pressure to close said valve, and a control valve operable by variations in suction load to by-pass fluid pressure from one side of said plunger to the other.

12. A compressor unloader comprising, a clearance pocket communicable with the compressor displacement chamber at the end of the compression stroke, an unloading valve for controlling communication between said pocket and said displacement chamber, a plunger operable by compressor discharge pressure to close said valve, and a control valve operable by variations in suction load to by-pass fluid pressure from one side of said plunger to the other.

13. A compressor unloader comprising, a clearance pocket communicable with the compressor displacement chamber at the end of the compression stroke, an unloading valve for controlling communication between said pocket and said displacement chamber, a plunger operable by compressor discharge pressure to close said valve, and a control valve operable by variations in suction load to by-pass fluid pressure from one side of said plunger to the other.

14. A compressor unloader comprising, a clearance pocket communicable with the compressor displacement chamber and being constantly restrictively vented to the compressor suction, an unloading valve for controlling communication between said pocket and said displacement chamber, a valve actuating plunger operable in an auxiliary chamber segregated from said pocket, means for admitting compressor discharge pressure to said auxiliary chamber on one side of said plunger, and a by-pass valve operable by variations in compressor suction to throttle the admission of compressor discharge pressure to said auxiliary chamber and to by-pass said pressure around said plunger.

CHARLES G. BACH. 30
